UNITED STATES PATENT OFFICE.

ABEN E. JOHNSON, OF HASTINGS, MICHIGAN, ASSIGNOR TO HASTINGS MANUFACTURING COMPANY, OF HASTINGS, MICHIGAN.

VEHICLE CURTAIN WINDOW.

Application filed November 18, 1920, Serial No. 424,940. Renewed May 25, 1923.

To all whom it may concern:

Be it known that I, ABEN E. JOHNSON, a citizen of the United States, residing at Hastings, county of Barry, and State of Michigan, have invented certain new and useful Improvements in Vehicle Curtain Windows, of which the following is a specification.

This invention relates to improvements in vehicle curtain windows.

The main objects of this invention are to provide a vehicle curtain window which is satisfactory for use in the manufacture of the vehicle curtains at the factory, or may be employed as a repair means for vehicle curtains in the hands of the users; the same being easily applied by an unskilled person and without the use of special tools.

Further objects and objects relating to structural details, will definitely appear from the detailed description to follow.

I accomplish the objects of my invention by the devices and means described in the following specification. The invention is clearly defined and pointed out in the claim.

A structure which is a preferred embodiment of my invention is clearly illustrated in the accompanying drawing, forming a part of this specification, in which:

Fig. I is a rear elevation of a vehicle top provided with a curtain embodying the features of my invention.

Fig. II is an enlarged elevation of one of the windows, the curtain being partially broken away.

Fig. III is an enlarged detail section on a line corresponding to the section line 3—3 of Figure II.

In the drawing similar reference characters refer to similar parts throughout the several views.

Referring to the drawing, 1 represents the vehicle top and 2 the rear curtain thereof. The curtain is provided with window openings 3. The panes 4 are of glass. I provide a supporting frame for each pane, comprising a pair of sheet metal frame members 5 of crowning cross section disposed face to face, with their outer edges overlapping the edges of the curtain around the window opening and their inner edges overlapping the pane, as clearly shown in Fig. III. The frame members are provided with continuous beads 6 at the top of their crowns, the beads adding to the rigidity of the frame

members. Clamping bolts 7 are disposed through the frame members at the outer sides of their beads and clamp the edges of the frame members upon the curtain and pane with a spring gripping action. The frame members have indentations 8 around their bolt holes, whereby the indented portions are clamped upon the curtain, as shown in Fig. III. This prevents the distortion of the frame members and also secures a direct clamping of the curtain at the bolts. The frame members are by this means secured to the curtain with their edges in spring clamping engagement therewith, and the curtains are also directly clamped by the indented portions, so that the curtain will not pull out from between the frame members even under very severe stress.

My improvements are particularly well adapted for use in repairing curtains in the hands of the users, and for repair work generally, but they are also desirable in new work, as the panes are held in a very satisfactory manner and the parts are simple and economical to produce and quickly and economically assembled in a curtain.

Having thus described my invention, what I claim as new and desire to secure by Letters Patent, is:

In a vehicle curtain window, the combination with a curtain having a window opening therein, of a pane of less dimensions than that of the window opening, and a supporting frame for said pane comprising a pair of sheet metal frame members disposed face to face with their outer edges overlapping the edges of the curtains around said opening and their inner edges overlapping said pane, said frame members being of crowning cross section and having continuous beads at the top of their crowns, and clamping bolts disposed through said frame members and curtain, said frame members being indented around their bolt holes whereby the edges of the frame members clamp the pane and curtain with a spring gripping action and the indented portions are clamped upon the curtain.

In witness whereof, I have hereunto set my hand and seal in the presence of two witnesses.

ABEN E. JOHNSON. [L. S.]
